CLAIM

The ornamental design for a cutting device as shown and described.

DESCRIPTION

FIG. 1 is a front and left perspective view of a cutting device;

FIG. 2 is an enlarged partial view of FIG. 1;

FIG. 3 is a front view of the cutting device;

FIG. 4 is a rear and right perspective view of the cutting device;

FIG. 5 is an enlarged partial view of FIG. 4;

FIG. 6 is a rear view of the cutting device;

FIG. 7 is a right side view of the cutting device;

FIG. 8 is a left side view of the cutting device;

FIG. 9 is a partial enlarged view taken from FIG. 8 without broken line environment in order to show aspects of the design not otherwise apparent; and,

FIG. 10 is a partial enlarged perspective view taken from FIG. 9 without broken line environment.

(Continued)

The long dash broken lines are directed to environment and form no part of the claimed design. The dot-dash broken lines indicating the enlarged portions of the design form no part of the claimed design.

1 Claim, 9 Drawing Sheets
